IRONING MACHINE STRUCTURE

John A. Castricone, Peoria, Ill., assignor to Alter-
fer Bros. Company, Peoria, Ill., a corporation of
Illinois

Application September 13, 1939, Serial No. 294,624

1 Claim. (Cl. 38—61)

This invention relates to domestic ironing machines and particularly to a novel structure which permits cheaper and more modern manufacturing arrangements as well as providing betterments in both utility and service.

Heretofore domestic ironing machines have been constructed as a single unit with a mechanism attached in parts on the cabinet. After practically complete assembly the ironer as a unit was then painted. This represents an older order or type of manufacture as contrasted with the more modern group line assembly methods as used in the manufacture of washing machines, refrigerators, and automobiles.

Modern paint or enamel finishes as used on such modernized products as automobiles, refrigerators, and washing machines require high temperature drying or baking and this requirement practically necessitates a separation of the product in units which may be handled and processed conveniently.

The conventional unitary structure of domestic ironing machines is ill suited to such treatment and it is the particular object of this invention to provide improved structure wherein the cabinet and mechanism could be assembled and painted as separate units and then afterward combined into a complete machine.

Another object is to provide improved ironing machine structure wherein the stresses of the mechanism are carried on a special frame within the cabinet designed to carry these stresses rather than to apply them to the cabinet as a whole and thus provide a better and more economical use of materials.

A still further object is to separate the ironer into various units which would permit better accessibility and more effective and economical service of the machine.

Other objects and benefits will be disclosed in the following descriptions and drawings in which:

Fig. 1 is a front isometric view of a domestic ironer complete as will illustrate a preferred embodiment of my invention;

Fig. 2 is a similar front isometric view of the ironer cabinet complete less all mechanism;

Fig. 3 is an enlarged broken bottom view of the ironer cabinet illustrated in Fig. 2, showing a sub-frame spot welded in position and which will be further explained in detail;

Fig. 4 is a broken cross sectional elevation view showing the top of the cabinet and sub-frame with operating mechanism assembly in place;

Fig. 5 is an enlarged isometric view of the

ironer drive mechanism with motor attached; and

Fig. 6 is an enlarged reverse side isometric view of the ironer gear case and head showing mounting bosses by means of which the case will be attached to the cabinet, as will hereafter be explained.

Now referring to the drawings, and at the outset particularly to Fig. 1, I designate the base of my ironer cabinet by the numeral 10, and hingedly attached to the base 10 are end shelves 11 and 12 and a cabinet top member 13. Mounted in the base member 10 with the top flush with the cabinet top is a gear head member 14 which is well illustrated in Figs. 5 and 6. On the gear head 14 is mounted an ironer roll 15 by means of the trunnion tube 15', as clearly shown in Figs. 4 and 6. An ironer shoe 16 is mounted in coacting relationship with the roll 15 by a support bracket 17, as will later be explained. An electric control panel 18 is hingedly mounted in the base 10 and when in normal use is positioned as shown in Fig. 1, but when stored may be hinged inwardly to properly house the control panel and protect it from dust. A knee control 19 is mounted in the left section of the cabinet 10, a hand control 20 is mounted in the right-hand upper section of the cabinet and a foot control treadle 21 is pivotally mounted between the upper sections of the cabinet.

In Fig. 2, I show the cabinet complete with all attached cabinet members, but less all the operating mechanism. It will be apparent from a study of Fig. 2 that this cabinet can be assembled complete and properly painted or enameled employing high temperature oven baking methods, while in no way affecting the operating mechanism. It will be obvious that the cabinet member proper is subject to most handling and use and, therefore, it would be decidedly advantageous to paint the cabinet with high baked synthetic enamels, which require higher temperatures than the operating mechanism could properly withstand.

I have now explained the structure employed, whereby the separation of the cabinet proper from the operating mechanism is made practical.

Referring to Fig. 3, which is a broken bottom view of the cabinet 10, and Fig. 4, which is a broken cross-sectional elevational view, I show a sub-frame structure welded within the cabinet, which is designed to withstand all the operating stresses. Channel sections 22 and 23 are spot welded within the frame 10 by attachment to the cross members 10' and 25. These channel sec-

tions are positioned together at the bottom by a tie-plate 24, as clearly disclosed in Figs. 3 and 4. It will be appreciated that by this structure I have provided a rigid sub-frame, and later I have shown how my mechanism is attached to this sub-frame and is supported by it in a manner which relieves the balance of the cabinet from all operating stresses. It will be appreciated that by making this rigid sub-frame, the balance of the cabinet can be reduced in thickness or gauge, thereby permitting the more economical use of materials, because the heavier sections are in the sub-frame, which is concealed within the frame, and which need not be of highly finished expensive roll stock.

In Fig. 3 I show an opening 27 through which operating mechanism 36 and 37 may be extended and around which is mounted the support bracket 17 by means of the cap screws 26, as is clearly shown in Fig. 4. The rocking shaft 36 is readily supported in the cross members 10' and 25, and the stresses produced by this mechanism are firmly resisted by the sub-frame and the bracket 17 bolted around the opening 27. In this manner the stresses are transmitted to the sub-frame and not transferred to the light base stand.

Now referring to Fig. 6, I clearly show threaded bolting bosses 28 on the lower inside face of the gear head 14. These bolting bosses register with holes 28' in the cross-wall 10' of the cabinet 10, as clearly shown in Fig. 2. Similarly, the holes 26' register with holes in the bracket 17 to permit its attachment by means of the cap screws 26. It will be appreciated that the gear head 14 may be passed through the top opening 30 in the cabinet 10 and securely attached to the sub-frame by means of the cap screws 30 into the threaded bosses 28, as clearly shown in Fig. 4.

It will be appreciated that by this structure I have provided means whereby the entire gear head is effectively supported on the sub-frame as heretofore described.

Again referring to Fig. 6, I show a rocking lever mechanism 31 which is attached to the interior mechanism in the gear case by means of the cap screws 32. This rocking lever mechanism has a pin 33 and bracket 34 integral therewith, which is attached to the rock shaft 36, as shown in Fig. 4. By this structure I provide means whereby the interior mechanism in the gear head 14 is attached to the rock shaft 36, which actuates the lever 31 to rock the shoe 16 into and out of ironing relationship with the roll 15. It

will be appreciated that this structure provides means whereby the various elements of the mechanism may be handled as distinct units and afterwards assembled within the frame to coact as an integral ironer mechanism.

In Fig. 5 I show how the electric motor 38 is attached to the gear head 14 by means of the mounting bracket 39, bolting bosses 40 and cap screws 41. It will be appreciated that by this structure the motor may be attached after complete assembly and thereby eliminating any possibility of damage to the motor in any of the finishing or baking operations. This is another illustration of the general theme of my invention, whereby the ironer is constructed of various assemblies as best suited for economical manufacturing and afterward assembled into a complete unit.

Although in the foregoing I have described structures particularly adapted for economical manufacturing, it will now be appreciated that the structure is particularly well adapted for effective servicing of the machine. For instance, should an ironer cabinet meet with an accident and be damaged to an extent requiring a new cabinet, such a new cabinet could be readily provided and the service man would have no difficulty in dismantling the old mechanism and applying it to the new cabinet. As another example, if the gear head 14 should in some way be defective, a new gear head could be supplied and attached to the ironer without in any way disturbing the balance of the mechanism. Similarly, the shoe and its actuating mechanism could be readily dismantled, and a new shoe supplied.

Having thus described my invention, I now claim as new:

In a domestic roll ironer, a cabinet unit, said cabinet unit including a main frame having a table top to support ironed clothes, end shelves and cover assembled and finished as a unit, a sub-frame attached and concealed within said cabinet, a gear head mechanism which may be assembled and finished as a unit, an ironer shoe mechanism which may be assembled and finished as a unit, and means to connect and mount said units in co-acting relationship on said frame, said means being completely concealed under the surface of said cabinet whereby the ironer may be assembled as a complete ironer with no attachment means normally visible.

JOHN A. CASTRICONE.
